UNITED STATES PATENT OFFICE.

HARRY W. MACDOUGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

NUMBER-INDICATING SYSTEM.

Application filed May 24, 1924. Serial No. 715,511.

This invention relates to number indicating systems, and more particularly to number indicating systems adapted for use in telephone exchanges, and is especially adapted for use 5 in conjunction with automatic telephone exchange systems.

The object of this invention is the provision, in telephone systems where operators are employed for manually extending connections over trunks leading to succeeding switching devices, of means for indicating to the operator the identity of an automatically selected trunk to be used by her in extending such connections.

15 In accordance with this invention where a trunk has been automatically selected, various circuits including resistance networks are established in succession over a single pair of wires to a group of register relays 20 which may or may not be operated in various combinations depending upon the resistance network used causing various circuits to be closed to light certain lamps which when lighted indicate to the operator the particular 25 trunk circuit selected.

Referring to the drawing, which constitutes a part of the disclosure, Figs. 1 to 4 inclusive, when arranged in the order shown in Fig. 5, illustrate so much of a telephone 30 system embodying this invention as is necessary to a comprehensive understanding thereof. Fig. 1 shows an operator's position in a manual office provided with cord circuits for extending subscribers' lines over interoffice 35 trunk lines outgoing to distant mechanical offices. Figs. 2 and 3 show two of a series of trunk selecting switches for automatically selecting an idle trunk outgoing from the operator's position to the desired mechanical 40 office. Fig. 4 illustrates the controlling and indicating equipment at the operator's position.

In the system disclosed connections are established by the operators in a manual originating office to any of a plurality of distant mechanical offices. For each mechanical office to which the operators in the manual office have access, there is provided a group 45 of interconnecting trunk lines terminating in switching apparatus in the mechanical office. These groups of trunks are multiplied 50 so as to appear in outgoing trunk jacks at

each of the manual operators' positions. The operator responds in the usual manner to a call initiated on any subscriber's line which 55 terminates at her position. Ascertaining the name of the called office and the number of the wanted line in that office, she manipulates the necessary apparatus at her position which causes the automatic selection of an idle trunk 60 outgoing to the called office, and the visual indication of the designation of the selected trunk. She then completes the connection by inserting the plug of the calling cord in the jack of the selected outgoing trunk and 65 by means of a dial or register sender proceeds to set the switches at the distant mechanical office to select the wanted line.

A plurality of selecting units are assigned to each group of interoffice trunks leading to 70 the distant mechanical offices, one of which offices is represented at DMO in Fig. 1. One of these selecting units consists of a plurality of step-by-step trunk selecting switches, such as 250 (Fig. 2) or 350 (Fig. 3) and a steering switch, such as 251 (Fig. 2). When the traffic between the manual office and the mechanical office is comparatively heavy a large group of interoffice trunk circuits is necessary. Inasmuch as the small step-by-step 80 trunk selecting switches 250 and 350 only have a capacity of 20 trunks, it is necessary to provide a plurality of these switches for the entire group of outgoing trunks. Assuming that the outgoing trunk group contains 160 85 trunks, 8 trunk selecting switches are provided, each having access to a group of 20 trunks, with means for successively operating the switches to select an idle trunk.

At each operator's position, a plurality of 90 office keys, such as 17, are provided, one for each distant mechanical office to which the operator has access. The depression of the office key 17 individual to any mechanical office initiates the selection of an idle trunk 95 leading to such mechanical office. Any one of the 8 trunk selecting switches, such as 250 or 350, may be the first to be set in operation dependent upon the group of 20 trunks in which an idle trunk is taken for use in the 100 last preceding connection. This switch hunts automatically and if an idle trunk is not found in this group of 20, returns to its normal position and initiates the hunting

operation of the next succeeding selector switch in the series. The next switch hunts over this group of 20 trunks and so on until one of the group of 8 switches finds an idle 5 trunk. A steering switch (251) is provided for each group of 8 trunk selecting switches and serves to control the operating circuits during the change-over from one switch to another.

10 In addition to the equipment thus far described, the operator's position in Fig. 1 is also provided with a number of indicating lamps (Fig. 4) for displaying before the operator the hundreds, tens and units designations of the automatically selected outgoing trunk. Since the trunk group is said to contain 160 trunks, only two hundreds lamps, the No. 0 (457) and the No. 1 (456) lamps are required. A group of sensitive and marginal relays are provided which are so controlled by a resistance network as to operate in various combinations to light the proper indicating lamps designating the number of the trunk seized by the trunk finder switch.

25 Having given a general outline of the system, the detailed description of the operations involved in establishing a connection will now be described.

30 Let us assume that the subscriber at the substation 1 (Fig. 1), whose line terminates in the jack 2 at a manual office, wishes to converse with the subscriber at substation 16, whose line terminates in the distant mechanical office DMO. When the receiver is removed at the substation 1, the line relay 4 is operated in series with the loop of the calling line, lighting the line lamp 5. The operator inserts the plug 3 in the jack 2, operating relays 6 and 8 and releasing the line relay 4, thus extinguishing the line lamp 5. The listening key 27 is operated, connecting the calling subscriber and the operator together and the name of the desired office and the number of the desired line are given to the operator by 45 the calling subscriber. The operator restores the listening key 27 to normal and depresses the office key 17, which corresponds to the name of the distant mechanical office DMO.

50 When the key 17 is depressed, relay 18 operates over an obvious circuit and locks by way of 19, 24, and 419 to ground. Relay 18 operated, closes a circuit to light lamp 404 as follows: battery, 26, 25, lamp 404, 419 to ground. The lamp 404 is lighted at this time to indicate to the operator that a trunk to the distant mechanical office DMO (Fig. 1) has not yet been picked.

60 Relay 18 operated, also closes a circuit to operate relay 300 as follows: battery, winding of relay 300, 23, 20 to ground. Relay 300 operated, closes a circuit to operate the stepping magnet 303 as follows: battery, winding of stepping magnet 303, 304, 305, 211, 208, 309, 318, 212, 209, 321, 328 to ground. Stepping magnet 303 operated, opens at 304 its own

operating circuit and releases, advancing the brushes 320 to 323 inclusive, one step in a counter clockwise direction to the first terminal in each of the arcs 310 to 313, inclusive. The trunk finder switch 350 is capable of hunting over a group of 20 trunks and the hunting lead of every busy trunk will be connected to ground, causing the trunk to test busy at the arc 311. Let us assume that every trunk to which the trunk finder switch 350 has access 75 is busy, in which case the first 20 terminals of the arc 311 will be connected to ground, as indicated in the drawing. With the brushes 320 to 323, inclusive, resting upon the first terminal of their respective arcs, the circuit previously traced will be closed to reoperate the stepping magnet 303 to ground by way of terminal 358 of arc 311. The stepping magnet opens at 304 its own operating circuit in the manner previously described and advances 80 its brushes one step in a counter clockwise direction to the next terminal in each of the arcs 310 to 313, inclusive. As we have assumed that all the trunks are busy, this cycle 85 of operations will continue until the brushes 320 to 323 are resting on the twenty-first terminal of their respective arcs, in which position a circuit will be closed to maintain the stepping magnet 303 operated, as follows: 90 battery, winding of the stepping magnet 303, 319, 210, 219, 317, 322, 316, 315, 314, 331 to ground. The stepping magnet 303 will remain operated until the steering switch 251 advances, as hereinafter described. With the stepping magnet 303 operated, a circuit is now 95 closed to operate the stepping magnet 206 of the steering switch 251 as follows: battery, winding of the stepping magnet 206, 207, 213, 218, 324, 325, 326, 323, 306, 375, 327, 307 to ground. Stepping magnet 206 operated, 100 opens at 207 its own operating circuit and releases, advancing its brushes 210 to 215, inclusive, one step in a counter-clockwise direction, thus opening at the terminal 220 the holding circuit for the stepping magnet 303, 105 which now releases, thus advancing the brushes 320 to 323, inclusive, another step, in which position brushes 320, 322 and 323 are opened, brush 321 only remaining in contact with the terminal 328 of the arc 311. 110

115 The advance of the brushes 210 to 215 of the steering switch 251 causes the trunk finder switch 250 to operate and search for an idle trunk in the trunk group to which it has access. The stepping magnet 252 of the trunk finder switch 250 is now operated as follows: battery, winding of the stepping magnet 252, 253, 254, 211, 208, 309, 318, 212, 216, 271, 217 to ground. Stepping magnet 252 operated opens at 253 its own operating 120 circuit and releases, advancing its brushes 270 to 273, inclusive, one step in a counter-clockwise direction to the first terminal of their respective arcs 260 to 263, inclusive. Let us assume that the first ten trunks in 125 130

this trunk group are also busy, in which case ground will be connected to each of the first ten terminals of the arc 261 and the stepping magnet 252 will continue to operate and release, advancing the brushes 270 to 273, inclusive, step by step until the terminals associated with the eleventh trunk are reached. Let us assume that the eleventh trunk is idle, in which case the terminal 228 will be free 10 from ground, and accordingly, the stepping magnet 252 will not reoperate. A circuit will now be closed to operate relay 339 as follows: battery, winding of the stepping magnet 252, 253, 254, 211, 208, 309, winding 15 of relay 339, 338 to ground. It should be observed that relay 339 was short circuited while the trunk finder switches were hunting for an idle trunk due to the presence of ground either on the hunting lead 209 or on 20 the hunting lead 216, depending upon which trunk finder switch was in use. However, as soon as an idle trunk is found, the absence of ground on the hunting terminal removes the short circuit from the winding of relay 25 339, permitting it to operate. Relay 339 operated, connects solid ground at 337 by way of lead 318, brush 212, lead 216 and brush 271, to the terminal 228, thence to the associated hunting terminals of the same 30 trunk at all other trunk finder switches, causing this trunk to test busy to all other trunk finders.

Relay 339 operated, closes an obvious circuit to operate relay 330, thus extending lead 346 by way of 344, 342 and 234 to the brush 214 of the steering switch, and the lead 345 by way of 343, 341, and 233 to the brush 215 of the steering switch.

Having found an idle trunk, we now proceed to indicate the number of the trunk seized to the operator at the manual switchboard (Fig. 1). The trunks available to the trunk finder switch 250 are numbered from 20 to 39, and as the brushes 270 to 273, inclusive, are resting upon the eleventh terminal in each of the arcs 260 to 263, inclusive, we have picked trunk No. 30. It is accordingly necessary to indicate this to the operator by lighting the corresponding lamps, 030 (Fig. 4). The following circuit is now closed to operate relays 340, 451 and 453: battery, 26, 25, left windings of relays 453 and 451, 448, 346, 344, 342, 234, brush 214, 217, low resistance winding L of relay 340 to ground. Relays 451 and 453 operated, lock by way of their right windings and lead 359 to ground at 348. Relay 340 operated, operates relay 354 over an obvious circuit. Relay 354 operated, locks by way of 360 and 361 to ground under the control of relay 330. A circuit is also closed to operate relay 452 as follows: battery, left windings of relays 454 and 452, 447, 345, 343, 341, 233, 215, 227, 226, high resistance winding H of relay 340 to ground. Relay 452 operated, locks through its right

winding by way of 359 to ground at 348, but relay 454, which is marginal, does not operate due to the high resistance winding H of relay 340 in series with it.

Relay 451 operated, closes an obvious circuit to operate relay 449, thus transferring the leads 345 and 346 to circuits including the windings of relays 441 and 445 and relay 446, hereinafter more fully described. Relay 449 operated removes ground from the "no 70 trunk" lamp 404 extinguishing it, as an indication to the operator that an idle trunk has been found. The operation of relay 449 also opens the locking circuit for relay 18 (Fig. 1) which releases. Relay 449 is designed to be slow to operate so that it will not operate immediately relay 451 operates, but will delay its operation long enough for relay 340 to operate, permitting relay 354 to operate and lock under control of relay 330. 85 With the leads 345 and 346 connected to the windings of relays 441 and 445, and relay 446, respectively, the leads 345 and 346 are connected to ground instead of battery, permitting relay 340 to release. It should be observed that relays 441, 445 and 446 will not operate under this circuit condition, preventing the possibility of false registration due to premature operation. Relay 340 released, closes a circuit to operate relay 355 as follows: battery, winding of relay 355, 362, 363 to ground. Relay 355 operated, transfers the leads 345 and 346 from the brushes 215 and 214 of the steering switch 251, to the brushes 273 and 272 respectively, of the trunk finder switch 250. It will be observed that the brush 272 is resting upon the open terminal 221. Hence, a circuit by way of lead 346 will not be closed and relays 441 and 445 will not operate. A circuit will be closed to operate relays 446 and 352 as follows: battery, armature 364 of relay 330 (Fig. 3), 336, 365, 308, 366, 367, 373, 368, low resistance winding L of relay 352, 369, 222, terminal 223, brush 273, 224, 327, 370, 341, 343, 345, 405, 406, left winding of relay 446 to ground. Relay 446 operated, locks by way of its right winding and lead 359 to ground at 348. Relay 446 operated, closes an obvious circuit to operate relay 444, which in turn operates 115 relay 443, which in turn operates relay 442. Relays 442, 443 and 444 are designed to be slow to operate to insure the operation of relays 352 and 353 before leads 345 and 346 are transferred to the windings of relays 400 120 and 401, and relays 402 and 403, respectively. Relay 352 operated, closes a circuit to operate relay 353 as follows: battery, armature 364 of relay 330, 336, 365, 308, 366, 367, 373, 368, 371, winding of relay 353, 372, 361 125 to ground. Relay 353 operated, opens at 373 the operating circuit for relay 352, which releases. Relay 353 now locks over the following circuit: battery, armature 364 of relay 330, 336, 365, 308, 366, 367, 374, winding of 130

relay 353, 372, 361 to ground. A circuit is now closed to operate relays 400 and 401 as follows: battery, through the windings of relays 400 and 401 in parallel, 407, 408, 405, 5 345, 343, 341, 370, 327, 375, 376, 377, 378 to ground.

A circuit is now closed to light the 0 hundreds lamp (457) as follows: battery, armature 410 of relay 454, lamp 457, 411, 412 to ground. A circuit is also closed to light the 10 tens lamp 3 (430) as follows: battery, armature 413 of relay 401, lamp 430, 414, 415, 416, 409, 411, 412 to ground. A circuit is also closed to light the 0 units lamp (440) 15 as follows: battery, armature 417 of relay 403, lamp 440, 418, 420, 421, 422, 412 to ground.

Accordingly, the 0 hundreds lamp (457), the 3 tens lamp (430) and the 0 units lamp 20 (440) are lighted at the operator's position, indicating to the operator that trunk No. 30 in the first hundred has been seized. The operator now inserts the plug of the calling cord 10 (Fig. 1) in the jack 11, which is associated with the trunk circuit No. 30 which was seized by the trunk finder 250 operating relay 13 and lighting supervisory lamp 12. Relay 13 operated, connects ground by way of lead 21, to the terminal 228 of the trunk 25 finder 250, thus providing a substitute ground to cause the trunk to test busy after relay 339 releases in the manner hereinafter described. The operation of relay 13 closes a circuit to operate relay 333 as follows: battery, resistance 335, 334, winding of relay 333, 332, brush 270, terminal 260, 22 to ground. Relay 333 operated, opens at 302 the locking circuit for relay 300, which releases, and at 348, the locking circuits for the various relays 451, 452, 445, 446, 453, 454 and 441, releasing those relays which may happen to be operated. Relay 300 released, opens the circuit through the winding of relay 339, which also releases. Relay 339 released, 40 opens the circuit through relay 330, which releases, in turn releasing relay 354, which in turn releases relay 355. Relay 339 released, also opens the operating circuit for relay 333, which releases. The release of relay 330 opens the trunk indicating leads 343 and 344 and removes battery at its armature 364 and ground on its contact 361 from the winding of relay 353, which releases. The release of relay 451 releases relay 449 and the release of relay 446 allows relays 444, 443 and 442 to release in sequence.

The dialing key 28 is now operated, and the dial 29 is operated and released in accordance with the digits comprising the code of 60 the called line 16, in the distant mechanical office DMO, setting the switches 14 and 15 to extend the connection to the terminals of the called line. The called line 16 is signalled in a manner not shown, and upon responding, 65 relay 9 is operated, extinguishing the calling

supervisory lamp 12, and conversation takes place between the calling subscriber 1 and the called subscriber 16.

When the receiver is replaced upon the switchhook at the calling station 1, relay 8 70 releases and the supervisory lamp 7 is lighted. When the receiver is replaced upon the switchhook at the called station 16, relay 9 releases, and the supervisory lamp 12 is lighted. When the plugs 3 and 10 are removed from the jacks 2 and 11, relays 6 and 13 release and the circuit is restored to normal.

During the transfer of the leads 345 and 346 from one group of register relays to the 80 next group by the operation of relay 449 or 442, it is important that the succeeding group of register relays should not be prematurely operated by way of the resistance networks formerly used to operate the previous group 85 of register relays. To prevent such premature and false operation, each succeeding group of register relays is connected to the opposite side of the battery supply than that to which the preceding group was connected 90 and each succeeding resistance network is likewise arranged in this manner. The result is that when, for example, the relay 449 operates, the register relays 441, 445 and 446, encounter either grounded or open-circuit 95 conditions on leads 345 and 346 by way of brushes 214 and 215, and therefore will not operate. The operation of relay 355 extends leads 345 and 346 by way of brushes 273 and 272 to either an open-circuit condition, a battery circuit condition through the resistance network, or both, and circuits to operate relays 441, 445 and 446 or some particular combination of these three relays are closed. In like manner relays 400, 401, 402 and 403 105 are prevented from operating until either relay 349 or relay 352 has operated, and, in turn operated either relay 351 or relay 353.

What is claimed is:

1. In a telephone exchange system, an operator's position, a plurality of trunks at said position, a trunk finder, means for operating said trunk finder to seize the first idle trunk, and indicator devices including a plurality of marginal relays controlled progressively 110 over a single pair of leads, said relays being variably responsive to the setting of the trunk finder to indicate the particular trunk seized.

2. In a telephone exchange system, an operator's position, a plurality of trunks arranged in groups at said position, trunk finders, one for each group, a trunk finder selecting device, means controlled by said device for operating said trunk finders, whereby one of them seizes an idle trunk in one of said groups, and indicator devices controlled over a single pair of leads, said indicator devices being variably responsive to the settings of the selecting device and of the trunk finder used to designate the specific trunk seized.

3. In a telephone exchange system, an operator's position, a plurality of trunks arranged in groups at said position, trunk finders, one for each group, a trunk finder selecting device, means controlled by said device for operating said trunk finders, whereby one of them seizes an idle trunk in one of said groups, and indicator devices including a plurality of marginal relays variably responsive to the settings of the selecting device and of the trunk finder used to designate the specific trunk seized.

4. In a telephone exchange system, an operator's position, a plurality of trunks arranged in groups at said position, trunk finders, one for each group, a trunk finder selecting device, means controlled by said device for operating said trunk finders, whereby one of them seizes an idle trunk in one of said groups, and indicator devices including a plurality of marginal relays controlled progressively over a single pair of leads, said relays being variably responsive to the settings of the selecting device and of the trunk finder used to designate the specific trunk seized.

5. In a telephone exchange system, an operator's position, a plurality of trunks arranged in groups at said position, trunk finders, one for each group, a steering switch, means for associating the steering switch with any trunk finder, means controlled by the steering switch for operating the trunk finder thus associated, whereby it seizes an idle trunk, and indicator devices variably responsive to the settings of the steering and trunk finder switches to designate the specific trunk seized.

6. In a telephone exchange system, an operator's position, a plurality of trunks arranged in groups at said position, trunk finders, one for each group, a steering switch, means for associating the steering switch with any trunk finder, means controlled by the steering switch for operating the trunk finder thus associated, whereby it seizes an idle trunk and indicator devices controlled over a single pair of leads, said indicator devices being variably responsive to the settings of the steering and trunk finder switches to designate the specific trunk seized.

7. In a telephone exchange system, an operator's position, a plurality of trunks arranged in groups at said position, trunk finders, one for each group, a steering switch, means for associating the steering switch with any trunk finder, means controlled by the steering switch for operating the trunk finder thus associated, whereby it seizes an idle trunk, and indicator devices including a plurality of marginal relays variably responsive to the settings of the steering and trunk finder switches to designate the specific trunk seized.

8. In a telephone exchange system, an operator's position, a plurality of trunks ar-

ranged in groups at said position, trunk finders, one for each group, a steering switch, means for associating the steering switch with any trunk finder, means controlled by the steering switch for operating the trunk finder thus associated, whereby it seizes an idle trunk, and indicator devices including a plurality of marginal relays controlled progressively over a single pair of leads, said relays being variably responsive to the settings of the steering and trunk finder switches to designate the specific trunk seized.

9. An indicating device comprising a plurality of control combinations, each consisting of a plurality of resistance networks, a plurality of registers, a pair of leads for associating the registers with a particular control combination, and means for progressively transferring the leads from one resistance network of the control combination to another and from one register to another.

10. An indicating device comprising a plurality of control combinations, each consisting of a plurality of resistance networks, a plurality of registers, a pair of leads for associating the registers with a particular control combination, means for progressively transferring the leads from one resistance network of the control combination to another, and means for progressively transferring the leads from one register to another.

11. An indicating device comprising a plurality of control combinations, each consisting of a plurality of resistance networks, a plurality of registers, means for selecting any control combination, a pair of leads for associating the registers with the control combination selected, and means for progressively transferring the leads from one resistance network of the control combination to another and from one register to another.

12. An indicating device comprising a plurality of control combinations, each consisting of a plurality of resistance networks, a plurality of registers, means for selecting any control combination, a pair of leads for associating the registers with the control combination selected, means for progressively transferring the leads from one resistance network of the control combination to another, and means for progressively transferring the leads from one register to another.

13. An indicating device comprising a plurality of control combinations, each consisting of a plurality of resistance networks, a plurality of registers, means for selecting any control combination, a pair of leads for associating the registers with the control combination selected, and switching means responsive to the operation of a particular register for transferring the leads from such register and one of the resistance networks of the control combination to the next succeeding register and another resistance network.

14. An indicating device comprising a plurality of control combinations, each consisting of a plurality of resistance networks, a plurality of registers, means for selecting any control combination, a pair of leads for associating the registers with the control combination selected, switching means responsive to the operation of a particular register for transferring the leads to the next succeeding register, and switching means controlled by the operation of the first mentioned switching means for transferring the leads to another resistance network of the control combination.
15. An indicating device comprising a plurality of control combinations, each consisting of a plurality of resistance networks, a plurality of registers, means for selecting any control combination, a pair of leads for associating the registers with the control combination selected, switching means responsive to the operation of a particular register for transferring the leads to the next succeeding register, switching means controlled by the operation of the first mentioned switching means for transferring the leads to another resistance network of the control combination, and means effective during the switching operations for delaying the operation of the succeeding register until both switching operations are completed.
16. An indicating device comprising a plurality of control combinations, each consisting of a plurality of resistance networks, a plurality of registers, means for selecting any control combination, a pair of leads for associating the registers with the control combination selected, a relay responsive to the operation of a particular register for transferring the leads to the next succeeding register, and a relay controlled by the operation of the relay first mentioned for transferring the leads to another resistance network of the control combination.
17. An indicating device comprising a plurality of control combinations, each consisting of a plurality of resistance networks, a plurality of registers, means for selecting any control combination, a pair of leads for associating the registers with the control combination selected, a relay responsive to the operation of a particular register for transferring the leads to the next succeeding register, another relay controlled by the operation of the relay first mentioned for transferring the leads to another resistance network of the control combination, and means effective during the transfer operations for delaying the operation of the succeeding register until both transfer operations are completed.
18. In an indicating device, a plurality of control combinations comprising a plurality of resistance networks, means for selecting any control combination, a plurality of registering devices, a pair of leads for associating

the registering devices with the control combination selected, means for progressively transferring the leads from one resistance network to another and from one registering device to another whereby the registering devices are progressively set, and a plurality of visible signals variably responsive to the settings of said registering devices.

19. In an indicating device, a plurality of control combinations comprising a plurality of resistance networks, means for selecting any control combination, a plurality of registering devices, a pair of leads for associating the registering devices with the control combination selected; means for progressively transferring the leads from one resistance network to another, means for progressively transferring the leads from one registering device to another, whereby the registering devices are progressively set; and a plurality of visible signals variably responsive to the settings of said registering devices.

20. In an indicating device, a plurality of control combinations comprising a plurality of resistance networks, means for selecting any control combination, a plurality of registering devices, a pair of leads for associating the registering devices with the control combination selected, and switching means responsive to the operation of a particular registering device for transferring the leads from such registering device and one of the resistance networks to the next succeeding registering device and another resistance network whereby the registering devices are progressively set, and a plurality of visible signals variably responsive to the settings of said registering devices.

21. In an indicating device, a plurality of control combinations comprising a plurality of resistance networks, means for selecting any control combination, a plurality of registering devices, a pair of leads for associating the registering devices with the control combination selected; switching means responsive to the operation of a particular registering device for transferring the leads to the next succeeding registering device, switching means controlled by the operation of the first mentioned switching means for transferring the leads to another resistance network of the control combination, whereby the registering devices are progressively set; and a plurality of visible signals variably responsive to the settings of said registering devices.

22. In an indicating device, a plurality of control combinations comprising a plurality of resistance networks, means for selecting any control combination, a plurality of registering devices, a pair of leads for associating the registering devices with the control combination selected; switching means responsive to the operation of a particular registering device for transferring the leads to the next succeeding registering

device, switching means controlled by the operation of the first mentioned switching means for transferring the leads to another resistance network, whereby the registering 5 devices are progressively set; means effective during the switching operations for delaying the setting of the succeeding registering device until both switching operations are completed, and a plurality of visible signals 10 variably responsive to the settings of said registering devices.

23. In an indicating device, a plurality of control combinations comprising a plurality of resistance networks, means for selecting 15 any control combination, a plurality of registering devices, a pair of leads for associating the registering devices with the control combination selected; a relay responsive to the operation of a particular registering device 20 for transferring the leads to the next succeeding registering device, a relay controlled by the operation of the relay first mentioned for transferring the leads to another resistance network, whereby the registering 25 devices are progressively set; and a plurality of visible signals variably responsive to the settings of said registering devices.

24. In an indicating device, a plurality of control combinations comprising a plurality of 30 resistance networks, means for selecting any control combination, a plurality of registering devices, a pair of leads for associating the registering devices with the control combination selected; a relay responsive to the 35 operation of a particular registering device for transferring the leads to the next succeeding registering device, another relay controlled by the operation of the relay first mentioned for transferring the leads to another resistance network, whereby the registering 40 devices are progressively set; means effective during the transfer operations for delaying the operation of the succeeding register until both transfer operations are completed, and a plurality of visible signals 45 variably responsive to the settings of said registering devices.

25. In a telephone exchange system, a plurality of lines, a selector for selecting said 50 lines, means for identifying the lines in said selector comprising combinations of current sources of different electrical characteristics individual to each of said lines, an indicator for indicating a line according to the identifying means selected, and means for operating 55 said selector to select and connect to said indicator a particular identifying means individual to the line selected.

26. In a telephone exchange system, a plurality of lines, line identifying means comprising combinations of current sources of different electrical characteristics individual to each of said lines, an indicator, a selector 60 for simultaneously selecting an idle line and an identifying means and connecting said

identifying means to said indicator, means for operating said selector, and means operable in said indicator responsive to said connection for indicating the line selected.

27. In a telephone exchange system, a plurality of lines, line number identifying means comprising combinations of current sources of different electrical characteristics individual to each of said lines, an indicator, a selector for simultaneously selecting an idle 70 line and an identifying means and connecting said identifying means to said indicator, means for operating said selector, and means operable in said indicator responsive to said connection for indicating the number of the 80 lines selected.

28. In a telephone exchange system, a plurality of lines, a selector with stationary and movable contacts for selecting said lines, means for identifying the lines in said selector comprising current sources of different electrical characteristics connected to said stationary contacts selectable in combinations individual to each of said lines, an indicator for indicating a line according to the 90 identifying means selected, and means for operating said movable contacts for selecting a line and an identifying means and connecting said identifying means to said indicator. 85

29. In a telephone exchange system, an operator's position, a plurality of lines at said position, an indicator, a selector with stationary and movable contacts for selecting said lines, means for identifying the lines in said selector comprising current sources of different electrical characteristics connected to the stationary contacts selectable in variable combinations for operating said indicator, means for setting said movable contacts in motion for simultaneously finding an idle line and an identifying means, and means in said indicator responsive to said identifying means for indicating the number of the idle line selected. 95 100 105

30. In a telephone exchange system, an operator's position, a plurality of lines at said position, a selector with stationary and movable contacts for selecting said lines, means for identifying the lines in said selector comprising current sources of different electrical characteristics connected to said stationary contacts selectable in variable combinations for operating said indicator, means for setting said movable contacts in motion for simultaneously finding an idle line and an identifying means, means for interconnecting said indicator and said identifying means by a single pair of conductors, and means in said indicator responsive to said identifying means for indicating the number of the line 110 115 120 125 selected.

31. In a telephone exchange system, an operator's position, a plurality of lines at said position, an indicator including a plurality of marginal electromagnetic devices, a selector 120 130

for selecting said lines, means for identifying the lines in said selector comprising combinations of current sources of different electrical characteristics individual to each of said lines, means for operating said selector to select and connect to said indicator a particular identifying means individual to the line se-

lected, and means responsive to said connection for operating certain of said marginal electromagnetic devices according to the 10 identifying means selected.

In witness whereof, I hereunto subscribe my name this 22 day of May A. D., 1924.

HARRY W. MacDOUGALL.
